(No Model.)

P. CAROLAN.

LIFE SAVING APPARATUS.

No. 375,047.

Patented Dec. 20, 1887.

UNITED STATES PATENT OFFICE.

PATRICK CAROLAN, OF CLEVELAND, OHIO.

LIFE-SAVING APPARATUS.

SPECIFICATION forming part of Letters Patent No. 375,047, dated December 20, 1887.

Application filed August 29, 1887. Serial No. 248,127. (No model.)

To all whom it may concern:

Be it known that I, PATRICK CAROLAN, of Cleveland, in the county of Cuyahoga and State of Ohio, have invented certain new and useful 5 Improvements in Marine Life-Saving Apparatus, of which the following is a specification.

This invention relates to apparatus for rescuing people from wrecked vessels, and has for its object to facilitate and lighten the labors of the crew, increasing the chances of 10 rescuing the crew and passengers from the wreck, and reducing the cost for such apparatus by saving and retaining all the ropes and other parts of the appurtenances which have 15 heretofore been lost or wasted.

The invention consists in the peculiar construction and arrangement of the parts of the apparatus, and in the method of operating it, whereby the aforesaid results are attained, 20 substantially as hereinafter described, and pointed out in the claims.

Referring to the accompanying drawings, Figure 1 is a perspective view of my new apparatus as seen in working order. The manner of placing it in order will be fully explained hereinafter. Fig. 2 is an enlarged detached view of the part of the rope forming 25 the tramway upon which the breeches-buoy travels, showing the means of attaching and 30 detaching it to the spar of the vessel, and Fig. 3 is an enlarged detached view of the breeches-buoy. Fig. 4 represents the block and tail cord on the line for hauling the breeches-buoys.

A represents a strong rope or cable, which, 35 when fixed in place, as seen in Fig. 1, forms a double cable tramway from the shore to the vessel. At the middle part of said cable I form a stiff bend or bow, B, as seen in Fig. 2, by combining with the rope a thick stout piece 40 of leather or other suitable material firmly bound together by winding with marline. Attached to this bow is a piece of rope, C, having several eyelets, c c, fixed within it, for a purpose hereinafter shown.

D is a hook, also attached to the bow B by 45 a short stout cord, b, and is also provided with a cord, d, the purpose of which will be explained.

E is a trestle for supporting the inner ends 50 of the cable A, consisting of a bar, e, having pins in each end which enter holes in the up-

per ends of legs f f. The bar e has cleats g g near each end for holding the cable spread apart, as shown. The two ends of the cable are tied together and are hauled tight by means 55 of blocks and tackle F, hitched to an anchor-post or other suitable object.

H is a rope playing in a pulley-block, h, to be attached to the mast of the vessel when the apparatus is in place. The inner ends of said 60 rope H are passed through pulley-blocks i i on the under side of the bar e. This rope is designed for hauling the breeches-buoys back and forth.

The breeches-buoys consist of ring-floats J, 65 composed of cork or any other suitable buoyant material, to which are attached open sacks K, the lower ends being closed by a puckering-cord, k, fixed loosely in a hem for that purpose. The rings J are provided with suspending-cords j j, united at their upper ends to a single cord having a snatch-block, L, attached, by which the breeches-buoys are suspended to travel on the cable tramways A A.

M is a shot-cord having a shot or ball, N, attached by means of a piece of chain n, to prevent the cord being burned off when the shot is fired from the gun O, which is of the usual kind.

Q is a cart for carrying the apparatus when 80 not in use, which I divide into two compartments by a central partition, the object of which is to enable the cable and ropes to be half-coiled into each compartment when stowed in the cart, with the bow B lying over the partition, so that when they are rapidly drawn out they may not become entangled.

The manner of arranging and operating this apparatus is as follows: When the crew with the apparatus have arrived upon the shore as 90 near the wreck as convenient, the gun is fired, carrying the shot-line over the mast of the vessel in the usual manner. Then the shore end of the shot-line is made fast to the tail-cord of the hauling-rope H, and a direction-board, having printed directions in English and other languages plainly printed or painted thereon, is also attached. This is now hauled out by a man on the mast of the wrecked vessel, who, following the directions, makes the said 95 tail-cord fast around the mast. Next one of life-saving crew makes one end of said haul-

ing-line H fast to the hook-line d of the hawser or cable A, and also ties the two ends of said hauling-line H together. Now then a part of the life-saving crew will haul out the 5 cable, while another part of said crew will clear the cable from the cart as it is hauled out. The man on the mast of the vessel will, as the directions instruct him, pass the strap or rope C around the mast above the tail-block h and 10 hook it by one of the eyelets onto the hook D, thus making the cable fast to the mast of the wrecked vessel. In the meantime, while this is being done, a board platform, if there is one, has been laid on the beach and the trestle laid 15 thereon, with the legs spread out flat on the platform, ready to be raised, the ends of the cable tied together, and the tackle E hooked thereto, with the other tackle-block hooked to the pennant of the anchor in the sand, or other suitable object. Then the cable is hauled taut by 20 the tackle and the fall of the tackle-line made fast. The cable is now spread apart and caught in the two cleats i i on the bar e. Now the captain at one end of the bar e and a 25 man at the other end will each raise the trestle while other men at the legs will secure them by a spanner, s. Now breeches-buoy No. 1 will snatch onto the left-hand cable or hawser, then the hauling-line H, or "whip," as it is properly called, will be made fast to the suspending-cord of the said breeches-buoy. Now one 30 of the life-saving crew—usually No. 7—will get into the said breeches-buoy and be hauled out to the wrecked vessel, when he will see that 35 the cable and whip tail-block have been properly made fast to the mast of the vessel, and when he has arrived out the crew on shore will snatch on breeches-buoy No. 2 to the right-hand cable, and also attach the right-hand side of the whip-line to the said No. 2 40 breeches-buoy and place the said whip-line in the pulley-blocks i i and then tie the whip-line together, thus making an endless rope for hauling the breeches-buoys back and forth. 45 Now then the apparatus is all ready for conveying the people on the wrecked vessel ashore, and the man of the life-saving crew who went out to the wreck places one of the unfortunates of the wreck into the breeches-buoy that conveyed him out, and signals to the shore-men to haul in, and while they are doing so the breeches-buoy No. 2 is going out. When the breeches-buoy No. 1 arrives 50 inshore, four men holding a sheet beneath it are prepared to receive the unfortunate one, who is let down by the captain untying the puckering-cord of the sack, and he, with another man, catching the person, who may be helpless, and placing him on the sheet, to be 55 conveyed to any place of safety. In the meantime the man at the wreck has placed a second person in breeches-buoy No. 2, and at a given signal No. 2 is conveyed to the shore, and so on in like manner all are brought ashore. 60

Now the man of the life-saving crew prepares to be hauled ashore and have the cable and whip-line hauled in after him. This he does by first casting off the tail-line of the tail-block h from the mast, then releasing the hook-line d, which has been bound around the hook D as a mousing, to prevent its becoming unhooked by accident or otherwise, and then tying the said tail-line to the said hook-line. This places the whip-line in connection with the hook for unhooking the cable at the proper 75 time. Having thus prepared the cable for release, he places himself in the breeches-buoy and is hauled ashore. In the meantime the other breeches-buoy has been detached from the cable. Now then to haul the cable and 80 whip-line ashore, the crew slacken up on the cable by letting go the tackle F; then by pulling on the whip-line the hook D is pulled out of the eyelet in the strap C, and the cable is freed from the mast and falls into the sea, and 85 is all together hauled in shore, and thus all of the apparatus is recovered and is ready for repeated use without loss or injury.

From the foregoing it will be seen that by the use of my improved apparatus a life-saving crew are enabled to do double the amount of work in the time usually employed with the old single cable, and their work far more easily performed, and renders the risks and hazards of saving unfortunately wrecked people far less.

With my improved breeches-buoy a helpless occupant is much easier placed in it and removed from it, and in case the breeches-buoy should become detached and drop into the sea, it acts as a life-preserved, and enables the occupant to keep his head above water and to float ashore, and thus his chances for rescue are more certain.

Having described my invention, I claim—

1. The breeches-buoy consisting of a ring-buoy, J, having suspending-cords j j, and a sack, K, suspended therefrom and provided with a puckering-cord in the hem of its bottom, constructed substantially as described, and for the purpose specified.

2. The combination, with tram-rope A, having its shore ends connected with a trestle and secured by means of tackle F to any suitable firm object, and provided with a stiffened band, B, of the binding extension-rope C, provided with the eyelets c c, and the hook D, also attached to the band B, near the extension C, and provided with the line d, by means of which the tram-ropes are removably attached to the mast of the wreck, substantially as and for the purpose specified.

PATRICK CAROLAN.
